ADJUSTABLE TRIANGLE

Kalman John De Juhasz, State College, Pa.

Application January 17, 1947, Serial No. 722,683

4 Claims. (Cl. 33—93)

1

My invention relates to improvements in an adjustable triangle for use by draftsmen, comprising two pivotally connected blades bounded by straight ruling edges which can be adjusted to a desired angular relationship to one another, one of said blades carrying a degree graduation and the other an index mark or a vernier for the setting of the desired angle.

Adjustable triangles of this general type have been known and used for a long time, but existing executions have the disadvantage that they incorporate protruding knobs and other raised portions on one side, as a consequence of which such triangles can be laid flat only on its one side on the drafting board.

The main objective of my invention is to eliminate knobs and raised portions protruding beyond the thickness of the blades, in virtue of which my adjustable triangle can be laid flat on the drafting board on both of its sides, whereby the laying out of lines symmetrically to a certain symmetry axis is facilitated. Further advantages of my invention are: fewness of parts, and simplicity of parts, as a consequence of which it is adapted for accurate and inexpensive manufacture.

I attain these objectives and advantages by the construction illustrated in the accompanying drawings, in which:

Figure 1 is a plan view of a preferred execution of my adjustable triangle containing rigidly incorporated angles of 90, 45 and 30 degrees;

Figure 2 is a cross sectional view taken along line 2—2 showing the pivot construction;

Figure 3 is a plan view of another pivot construction;

Figure 4 is a sectional view of the pivot construction shown in Fig. 3, taken along line 4—4;

Figure 5 is the plan view of another modification of the pivot construction;

Figure 6 is a sectional view of the pivot construction shown in Fig. 5, taken along line 6—6;

Figure 7 is the plan view of a modified execution of my adjustable triangle containing rigidly incorporated angles of 90, 45 and 22½ degrees; and

Figure 8 is the plan view of another modification of my adjustable triangle containing rigidly incorporated angles of 45 and 30 degrees.

Referring to Fig. 1 the two blades 1 and 2 are preferably made of transparent plastic material such as the well known Lucite, or Plexiglass, but can be made also of metal if absolute freedom from warping or other secular changes is desired; these have a thickness of about $\frac{1}{8}$ inch and are

2

bounded by straight ruling edges and a circular arc as shown. The circular portion of both blades is of reduced thickness, in our example about $\frac{1}{16}$ inch, in virtue of which the two blades 1 and 2 can be assembled together forming a structure of $\frac{1}{8}$ inch thickness, and can be rotated relatively to each other about the center of said circular portion and thereby the relative angular position of the several ruling edges can be set to the desired value. One of the said blades e. g., blade 1 is marked with a degree graduation 1a and the other, e. g., blade 2 carries an index mark 2a. As shown in Fig. 1 the degree mark on blade 1 coinciding with the index mark on blade 2 express the angle between the ruling edges 1c and 2c; from this reading the angles formed by the other straight edges of the two blades can be found by simple mental calculation. For more accurate setting of the angle it is possible, of course, to use on blade 2 a vernier scale instead of the index mark 2a in a manner well known in surveying, toolmaking and other protractor instruments.

In order to hold the two blades 1 and 2 together the circular portions of the two blades are formed with a large circular bore concentric with the circular portion, the periphery of which circular bore is chamfered about 45 degrees, or counterbored to form shoulders, and this circular bore engages with the correspondingly beveled or shouldered outside periphery of the clamp ring 3 which is inserted into the circular bore with a radial tension. The clamp ring 3 is preferably made of steel or other metal or material of high elasticity; it is similar to a split ring or retaining ring used in machine construction, and is formed preferably as a body of equal strength in order to produce an approximately uniform radial force along its entire peripheral length. In virtue of its radial tension the beveled periphery of clamp ring 3 tends to urge the two blades 1 and 2 together producing a smooth friction between the contacting surfaces of blades 1 and 2. I have found that by making the clamp ring of sufficient stiffness the resulting friction is fully satisfactory for drafting purposes, and the two blades 1 and 2 will retain their set angular relationship without any additional locking means, until the angular relationship of the two blades 1 and 2 is changed intentionally by manual force.

I have, however, invented a locking mechanism in case an additional security against unintended slippage is desired, e. g., for tool or template layout purposes. One form of this locking mechanism is shown in Figs. 3 and 4 and consists es-

sentially of a modification of the clamp ring 4 the two ends of which form the jaws 5 and 6 engaging with the cam 7 fitted with the handle 8 by means of which the cam 7 can be rotated with the thumb or finger. Thereby the two ends of the clamp ring 4 can be forced apart to produce a gripping action on the beveled periphery of the circular bores in the two blades 1 and 2. The cam is fitted into the space between the two jaws 5 and 6 by means of a recess in the jaws which prevents the cam from falling out sideways. It will be realized that after the cam 7 is inserted between the jaws 5 and 6, and the handle 8 is inserted into the cam 7, then the cam cannot fall out of engagement with the jaws 5 and 6 because the handle 8 limits the range of motion of the cam 7. It will be also realized that all this locking mechanism can be made of such dimensions which do not protrude beyond the thickness of the blades 1 and 2, in virtue of which the instrument is rendered reversible, and it will lie flat on its both sides on the drafting board. Also other means of forcing apart the two ends of the clamp ring 4 may be employed, as by wedges, spiral cams or their combinations.

I have found practical also another modification of the pivot construction, shown in Figs. 5 and 6 in which a clamp ring 9 is provided between the two blades 1 and 2 and the spreading ring 10. This clamp ring 9 is made of some soft material such as aluminum or plastic, exerting little radial force, the radial force being provided mainly by the spreading ring 10, which said spreading ring 10 can be made of steel wire of round or rectangular cross section, or stamped out of flat strip steel. In Figs. 5 and 6 a spreading ring of round wire is shown. The advantage of this construction is that the clamp ring 9 can be made of such material which wears more than the two blades 1 and 2, and thereby the wear on the more expensive blades is reduced and the useful life of the instrument is increased. It will be realized that a locking mechanism of the type shown in Figs. 3 and 4 can be incorporated also in this modification of the pivot.

Fig. 7 shows a modified form of the blades 11 and 12, in which the rigidly incorporated angles are 90, 45 and 22½ degrees. This gives, for a given size instrument longer ruling edges 11a and 12a as compared with the form shown in Fig. 1, at a sacrifice of the rigid angle of 30 degrees, which is not present in this case.

Fig. 8 shows another modification of the blade form, in which the two blades 13 and 14 are of identical form which is an advantage from the production point of view, and which also permits a greater total range of rotation. This advantage, however, involves the sacrifice of the 90 degree angle, and some reduction in the rigidity of the instrument.

Other modifications than those illustrated and described may be made by those skilled in this field, without deviating from the scope of my invention. What I claim is:

1. In an adjustable triangle comprising two blades of the same thickness, each blade having a circular portion, said circular portion of said blades being reduced to about one-half of the blade thickness, the said circular portions of said blades fitting into each other and rotatably pivoted to each other to permit setting of said two blades to the desired angle, concentric bores formed in the circular portions of said blades, 5 said concentric bores having chamfered edges, a radially expansible clamp ring having its outside periphery beveled towards the center of the ring to fit said chamfered edges of said bores formed in said blades to produce an axial force for urging the two blades into close mutual contact, when said ring is expanded substantially as described.
2. In an adjustable triangle comprising two blades of the same thickness, each blade having 10 a circular portion, said circular portion of said blades being reduced to about one-half of the blade thickness, the said circular portions of said blades fitting into each other and rotatably pivoted to each other to permit setting of said two blades to the desired angle, concentric bores formed in the circular portions of said blades, 15 said concentric bores having chamfered edges, a radially expansible clamp ring having its outside periphery beveled towards the center of the ring to fit over the chamfered edges of said concentric bores formed in said blades said clamp ring having its inside periphery grooved, and a spreading ring engaging said grooved inside periphery of said clamp ring for expanding said 20 clamp ring.
3. In an adjustable triangle as claimed in claim 1 said ring having a break therein providing ring ends, and means for forcing the two ends of said clamp ring apart to produce a locking action.
4. In an adjustable triangle as claimed in claim 1 said ring having a break therein providing ring ends, and a cam engaging with the two ends of said clamp ring for forcing the two ends of said clamp ring apart to produce a locking action.
